Primary Examiner — Cynthia Ramirez*Assistant Examiner* — Llorellys Martinez-Rivera(74) *Attorney, Agent, or Firm* — Birch, Stewart, Kolasch & Birch, LLP(57) **CLAIM**

The ornamental design for a headlight for motorcycle, as shown and described.

DESCRIPTION

FIG. 1 is a perspective view from the front side of a headlight for motorcycle.

FIG. 2 is a perspective view from the front side thereof.

FIG. 3 is a front elevation view thereof.

FIG. 4 is a left side elevation view thereof.

FIG. 5 is a right side elevation view thereof.

FIG. 6 is a bottom plan view thereof; and,

FIG. 7 is a referential view showing use thereof.

The portions of the headlight shown in broken lines are for the purpose of showing environmental structure only and form no part of the claimed design.
